WATER-COOLED FURNACE DOOR FRAME

Ottwin L. Braun, Pittsburgh, Pa., assignor to Reliance Steel Products Company, McKeesport, Pa., a corporation of Pennsylvania

Application February 8, 1954, Serial No. 408,755

6 Claims. (Cl. 122—499)

This invention is for a water-cooled door frame for use on open hearth furnaces and the like, and is for a door frame which is provided with an interior chamber or tank for reducing the destructive or corrosive effects of materials carried into the frame by the cooling water.

Door frames of the type referred to are generally of an arch or inverted U form having two legs which extend down the sides of the furnace door opening and a bridge across the top. This bridge has a water-cooled nose or lintel projecting laterally from one face thereof, and the bridge itself extends upwardly in front of the brick work of the furnace above the lintel.

The source of water supply for steel plants is frequently from small streams or bodies of water that may at times contain considerable foreign material. In the case of small streams the water very often becomes contaminated with algae and other vegetation that is likely to form corrosive acids within the door frame. It also carries a considerable amount of oxygen, and may carry various sediment-forming materials such as silt. This material most commonly accumulates in the lowest parts of the frame, which in this case are the lower terminals of the downwardly-extending legs. It produces oxidation of the steel plates which in turn reduces the rate of heat transfer through the metal, and it forms deposits which prevent the free circulation of water, and hence defeats the purpose of the water. The corrosion of the steel furthermore eventually weakens the structure, usually at a place which is quite vital, and interference with cooling allows the exposed metal to be adversely affected by the furnace heat.

The present invention has for its object to provide a door frame of the type referred to, having a chamber or tank constructed therein designed to trap and retain a considerable part of the materials above referred to and other substances which either form deposits or accelerate corrosion.

A further object of the invention is to provide in a furnace door of this type means for reducing the oxygen content of the water entering the more vital parts of the door frame.

These and other objects and advantages are obtained by my invention as will be hereinafter more fully described.

Generally my invention contemplates the provision within the upper part of such a door frame of a horizontally-extending partition, thereby forming in the upper part of the door frame a separate chamber or tank in which most of the foreign material carried by the cooling water will collect. Water is carried from this tank through a pipe which has its upper end opening into the tank at a level elevated above this horizontal partition into the lower part of the frame and there distributed in the usual manner, the water finally being led out through an outlet pipe in accordance with the usual practice. Additionally I prefer to provide in the chamber or tank above referred to a ferrous body which is susceptible to oxidation in the environment in which it is

2

employed, and which will first react with the oxygen and corrosive substances in the water, thus removing most of the oxygen harmlessly. It thereby prolongs the useful life of the door frame.

My invention may be more fully understood by reference to the accompanying drawings, in which:

Fig. 1 is a front elevation of a water-cooled door frame embodying my invention;

Fig. 2 is a top plan view thereof;

Fig. 3 is a transverse vertical section in the plane of line III—III of Fig. 1; and

Fig. 4 is a fragmentary section on a larger scale than Figs. 1 to 3 inclusive, the view being in the plane of line IV—IV of Fig. 1.

Referring to the drawings, the door frame generally is of customary construction, having two depending legs 2 and 3 closed at their lower ends, and having their upper ends opening into and connected by a bridge or arch 4. The door frame here shown is formed of sheet metal plates, there being a main back plate 5 which is shaped to the contour of the door, and which has its edges turned up to form a flange 6. The other plate 7 is of similar contour and is welded to the flange 6 around all of the edges of the structure, the plate 7 being spaced from plate 5 so that the door frame is hollow. The plate 7, which faces the brick work of the furnace, has a lintel or nose 8 extending horizontally thereacross, and which is generally in the form of a channel-shaped member closed at its ends welded to the plate 7 above and below a horizontally-extending slot 9 in the plate 7.

The construction as herein described is generally known in the art. According to the present invention a horizontal plate 10 is welded into the space between the plates 5 and 7 at a point above the nose or lintel 8. There is thus formed a tank or chamber 11 in the top of the frame which is separated from the water-circulating space under the partition 10. At the top of the door frame at one side there is a water inlet pipe 12 through which water enters the tank 11.

40 A vertical pipe which I sometimes refer to as a "stand pipe," passes through the partition 10 at the center of the door frame, this pipe being designated 13. It has its upper end well above the partition 10. Its lower end is connected into a T fitting 14, from which lead two 45 branch pipes 15, one extending down into each of the legs of the door frame. The pipes 15 are also provided with outlet nipples 16 that discharge water horizontally into the nose 8 of the door frame.

At the side of the door frame opposite the pipe 12 an 50 outlet pipe 17 passes from the under side of the partition 10 up through the chamber 11 and extends above the top of the door frame as shown.

In assembling the frame I prefer to also provide in the chamber 11 a perforate plate 18 formed of some readily 55 oxidizable material. It may, for example, be formed of expanded ferrous sheet metal, and the metal may be an ordinary low carbon steel. It preferably extends from the partition 10 to the top of the chamber 11, and may be tack-welded in place. It is structurally independent of the door frame, and tack-welding is employed only to retain it most effectively in place.

In operation, water is supplied to the door frame through the pipe connection 12. This water flows immediately into the tank or chamber 11 and can spread out and flow in all directions without obstruction. Due to the large area of the tank or chamber 11 the water will move at a low velocity, and at the same time it will become hot. Those materials in the water that tend to produce corrosion and deposits will tend to settle out and collect on the plate 10. This is one of the cooler parts of the door frame when the frame is in

operation, so that any materials that collect on top of the partition 10 will have very little effect on the efficiency of cooling or the life of the door frame. Since the top of the pipe 13 is located some distance above the partition 10, the water which flows out of the tank or chamber 11 will not pick up any deposited materials from the plate 10, consequently sedimentation can occur above the plate 10 and the water will be very materially cleaned before it flows out the pipe 13. When it flows out through the pipe 13, the water thereafter follows the usual course of water in water-cooled frames of this kind, passing down through the distributing system comprising the pipes 15 to the lowermost ends of the legs of the frame, as well as out the nipples 16 to specially cool the nose 8. The water is discharged from the lower ends of pipes 15 into the hollow interior of the legs close to the bottom. It will rise from this low point and eventually be carried out through the outlet pipe 17.

By thus trapping most of the sediment-causing materials at a harmless point in the upper part of the frame, sedimentation and the formation of deposits at the bottoms of the legs is reduced with the result that the life of the frame will be substantially prolonged.

Additionally the oxygen carried by the water, or other materials in the water that tend to corrode the metal of which the frame is constructed, will be brought much more effectively into contact with the expanded sheet plate 18, tending to rust or corrode this plate. This corrosive action and rusting will exhaust much of the corrosive substance and free oxygen from the water, so that the more vital parts of the frame will be protected from oxidation until the plate 18 has been substantially corroded away, or so far corroded as to be further ineffective.

According to my invention there is a clean-out plug 20 at each side of the door frame just above the partition 10, so that by unscrewing these plugs, sediment which accumulates on the plate 20 can be from time to time removed, and material that accumulates on the expanded metal plate 18 can be flushed away. The plugs 20 are provided in addition to the usual plugs 21 now commonly employed at the bottoms of the legs 2 and 3.

The interior of the nose 8 of the frame is preferably copper coated. The copper coating does not interfere with heat transfer, and resists oxidation or rusting and is less susceptible to corrosion than the metal of which the door frame is formed. By thus lining the interior of the nose 8 with copper, corrosion at this vital place will be reduced and retarded, while the rate of heat transfer will not be impaired.

Because of the relatively large capacity of the tank 11 as compared to the size of the pipe 12 and stand pipe 13, the water will flow with low velocity through the tank, and only the most buoyant materials can be carried by the water into the rest of the door frame. Because the plate 18 is ferrous material that can be quite easily oxidized or corroded under these conditions, and because it has a large exposed surface in proportion to its area, most of the oxygen and corrosive substances will react with this plate 18, instead of reacting with more important and more vital parts of the door frame. By reason of this, the overall useful life of the door frame will be substantially increased.

My invention, requiring only the addition of the plate 10 and the expanded metal sheet 18, and the use of the stand pipe, adds little, if anything, to the overall cost of the door frame, and does not complicate the assembling of the door frame, so that usual manufacturing methods can be employed and the user of the door frame does not have to alter his furnace design in any way to make use of my invention. My door frame can be used as a replacement for present frames with no

alteration of furnace design, and when these improvements are incorporated, the useful life of the frame will be substantially extended, and the cooling water will be more effectively used throughout the life of the door frame.

While I have shown and described one specific embodiment of my invention, it will be understood that this is by way of illustration, and that various changes and modifications may be made within the contemplation of my invention and under the scope of the following claims.

I claim:

1. A water-cooled furnace door comprising two formed metal plates joined together in spaced relation and forming an arch-like structure with a horizontal hollow bridge portion and depending hollow legs, the plates being sealed to each other so that the space between them is water-tight, a hollow lintel projecting horizontally from one of the plates near the lower edge of the bridge portion with the interior of the lintel opening into the interior of the bridge, a horizontal partition inside the bridge above and adjacent the lintel joining the two plates and dividing the interior of the bridge portion to provide a settling tank above the level of the partition, means for supplying cooling water to the tank, a conduit extending from a level above the bottom of the tank into the interior of the bridge below the partition whereby a substantial layer of non-circulating water is provided upon the said horizontal partition and below the level of the upper end of the conduit, and a water discharge pipe through which water is discharged from the interior of the door frame below the said horizontal partition.

2. A water-cooled furnace door frame as defined in claim 1 in which said conduit comprises a pipe passing through the partition with its upper end positioned above the partition and its lower end connected to a distributing pipe system that conducts water to the lower portions of the legs.

3. A water-cooled furnace door frame as defined in claim 1 having corrodible material in the separate tank which is structurally independent of the door frame and with which oxygen and corrosive elements in the water may react upon first entering the tank and out of contact with the water after it has entered the said conduit.

4. A water-cooled furnace door frame as defined in claim 1 having corrodible material in the separate tank which is structurally independent of the door frame and with which oxygen and corrosive elements in the water may react, said corrodible material comprising a vertical perforate sheet of ferrous metal placed edgewise in the tank and extending across the greater portion of the full width of the door frame.

5. A water-cooled furnace door frame as defined in claim 1 in which said conduit comprises a pipe passing through the partition with its upper end positioned well above the partition and its lower end connected to a distributing pipe system that conducts water separately to the lower portions of each of the legs and into the lintel.

6. A water-cooled furnace frame as defined in claim 1 in which opposite edges of the door frame have removable cleanout plugs at opposite ends of the tank at the level of the top of the partition.
